CLAIM

The ornamental design for a digital control pendant assembly for machine tools, as shown and described.

DESCRIPTION

FIG. 1 is a front elevational view of a digital control pendant assembly for machine tools, showing our new design.

FIG. 2 is a right side elevational view thereof.

FIG. 3 is a top plan view thereof.

FIG. 4 is a bottom plan view thereof.

FIG. 5 is a rear elevational view thereof.

FIG. 6 is a left side elevational view thereof.

FIG. 7 is a top plan view thereof, with the parts shown pivoted on vertical axes.

FIG. 8 is a front perspective view thereof, shown with the support arms omitted for convenience of illustration.
